UNITED STATES PATENT OFFICE.

HILAND H. KENDRICK, OF FULTON, NEW YORK.

SASH-LOCK.

SPECIFICATION forming part of Letters Patent No. 650,844, dated June 5, 1900.

Application filed May 8, 1899. Serial No. 715,950. (No model.)

To all whom it may concern:

Be it known that I, HILAND H. KENDRICK, a citizen of the United States, and a resident of Fulton, in the county of Oswego, in the 5 State of New York, have invented new and useful Improvements in Sash Locks and Catches, of which the following, taken in connection with the accompanying drawings, is a full, clear, and exact description.

10 The object of this invention is to provide a simple, convenient, and efficient sash lock and catch which shall be capable of locking the sash in any desired open position as well as in its closed position and shall effectually 15 prevent the sash from rattling and shall also have the lock or catch proper or the main portion of the device shielded and concealed, so as to protect it from dust and from water during the operation of washing the window 20 and also avoid defacing the sash and window-casing; and to that end the invention consists in certain peculiarities in the construction of parts and in certain novel combinations and arrangements of elements, substantially 25 as hereinafter described, and particularly set forth in the claims.

In the annexed drawings, Figure 1 is a face view of that portion of a window to which my invention is applied. Fig. 2 is a horizontal 30 transverse section on line X X in Fig. 1. Fig. 3 is a vertical transverse section taken in a plane passing through the sash lock and catch. Fig. 4 is a horizontal transverse section of a modification of my invention, and 35 Fig. 5 is a detached plan view of the plate used in said modification for guiding and sustaining the outer end of the push-bar.

Similar letters of reference indicate corresponding parts.

40 A and A' represent one of the sides and faces, respectively, of the window-casing.

C and C' denote the upper and lower sashes, respectively.

D represents one of the vertical outer guide-strips or shoulders projecting from the window-casing.

I is the usual parting-strip, which projects from the window-casing to separate the two sashes, and L denotes the so-called "stop,"

50 which is secured to the casing to confine the lower sash in the window.

a represents the rectilineally-movable push-

bar, which is disposed at right angles to the plane of the sash and by means of which said sash is forced outward against the aforesaid 55 shoulder projecting from the casing and is thereby locked on said shoulder.

I preferably interpose between the sash and push-bar a bite b, which is pressed against the front of the corner portion of the sash by 60 said push-bar in locking the sash. A vertical metal strip c, attached to said portion of the sash, serves to protect the same from wear and abrasion by contact with said bite. The aforesaid push-bar and bite are both 65 shielded and concealed by the stop L, which is placed over them. The bite b is formed on a block b', which slides in a shoe d, which is countersunk in the side casing A and securely confined therein. It will be observed 70 that the bite b projects laterally from a place between the ends of the block b' and forms, with the free end of said block, an approximately L-shaped portion which receives and engages the corner of the sash. It will also 75 be observed that one corner of said block is cut away to form a space bounded on two sides by walls of the shoe d and on the other two sides by the walls of said cut-away portion for the admission of the spring e, which 80 latter thereby bears against the block at a place out of line with the bar in opposition to which it acts and about on a line with the center of the block. The portion of the block which is engaged with the wall of the shoe 85 projects forward, as shown, to form an extended bearing against said shoe, thus compensating for the loss in the amount of the bearing-surface occasioned by removing the corner of the block. This specific construc- 90 tion is advantageous in that it overcomes any tendency to looseness or wabbling of the parts when in action and at the same time enables the parts to be of small size and compact form. Said shoe is formed with guides 95 d' d', which are parallel with the push-bar and sustain between them the bite-block b'.

e represents a spring seated in the end of the shoe adjacent to the sash and pressing the bite-block b' in opposition to the push-bar a, and thus automatically relieving the sash from the outward pressure of the bite b when the latter is relieved from the pressure of the push-bar.

Various means may be employed for imparting longitudinal movement to the push-bar. Two of such means are illustrated in the annexed drawings, in which Figs. 2 and 3 show the push-bar to consist of a revoluble screw working in a nut *n*, formed on one end of the shoe *d*. The free or protruding end of said push-bar has attached to it a suitable knob *o*, by which to turn said bar. The engagement of the stationary nut *n* with the revolving push-bar *a* causes the latter to move longitudinally, and in turning it in one direction it forces the bite *b* toward the sash and presses the sash outward against the vertical guide or shoulder projecting from the window-casing, and thereby clamps the sash in its position. In turning the push-bar in the opposite direction it is caused to recede from the bite *b*, which is then pushed from its engagement with the sash by force of the spring *e*. I do not, however, limit myself to the use of said screw-threaded push-bar and nut, inasmuch as the same effect may be obtained by means of a plain rectilinearly-sliding bar forced toward the bite *b* by means of a cam-disk *f*, bearing on the protruding end of the push-bar and fastened to a thumb-piece *g*, which is pivoted on a stud-pin *i*, screwed or otherwise firmly secured in a socket *l*, fastened 25 in a window-casing *A'*, as shown in Fig. 4 of the drawings. Said socket is formed on an annular plate *h*, resting on the face of the casing and provided with a plurality of apertures *t t*, as shown in Fig. 5 of the drawings. 30 The end of the push-bar passes through one of said apertures and is thus guided longitudinally and prevented from yielding laterally to the pressure of the cam-disk *f*. By turning the thumb-piece *g* the cam-disk is caused 35 to traverse the end of the push-bar and push the same endwise in opposition to the spring *e*.

In the operation of either of the described means for actuating the push-bar the latter is caused to press the bite *b* firmly against 40 the sash, and thereby clamp the same on the parting-strip *I* or on the guide-strip *D*, according to which of the two sashes the sash-lock is arranged to engage.

It will be observed that by the described 45 outward pressure of the sash against the shoulder projecting from the window-casing I effectually prevent the sash from rattling when said sash is locked by my improved lock and catch. It will also be observed that there 50 are two distinct and separate locking means—one for each sash—each including a block to engage its sash and a push-bar for the block. By thus providing each block with a separate 55 push-bar (instead of operating them in unison 60 by means of a device common to both and which when operated forces one in one direction and the other in the other direction, as heretofore) the sashes may be independently 65 locked and unlocked and one sash may be forced against one window-strip while the other sash is forced against another window-strip. The "bite" of one block is received by

a recess *L'*, formed in the strip or stop *L*, while the bite of the other block is received in a recess *I'*, formed in the parting-strip *I*. Furthermore, by placing the push-bar and bite in the window-casing back of the stop *L*, I effectually shield and protect the principal parts of the sash-lock from dust and water in the washing of the window and also avoid marring the window by the presence of the sash-lock.

What I claim as my invention is—

1. The combination with a window-casing, having an outer guide-strip, a recessed parting-strip and a recessed stop; and the upper and lower sashes; of a block, having a bite projecting laterally therefrom into the recess in the parting-strip and engaging the lower sash; a bar operated to force said block inward and lock the sash against the outer guide-strip; a separate block, having a bite projecting laterally therefrom into the recess in the stop and engaging the upper sash, and a bar operated to force said block inward and lock said upper sash against the parting-strip, substantially as described.

2. The combination with the window-casing and the upper and lower sashes, of means for locking said sashes independently, said

means embodying a pair of shoes countersunk in the casing and attached thereto, each

of said shoes having a nut at one end disposed axially at right angles to the plane of

the sash, guides formed in each shoe parallel

with the eye of the nut thereof, a pair of disconnected bites, one for each sash, sliding in

said guides, and a pair of disconnected and

independently-operated screw-rods extending

through the eyes of said nuts and engaging

said bites, substantially as described.

3. The combination, with the sash and

window-casing, of a shoe countersunk in said

casing and secured thereto, a nut formed on

one end of said shoe and disposed axially at

right angles to the plane of the sash, a screw

working in said nut, a bite sliding in said

shoe and actuated by the screw to force the

sash outward and a spring seated in the shoe

and forcing the bite in opposition to the screw

as set forth.

4. The combination with the window-casing and the upper and lower sashes, of means for locking said sashes independently, said

means embodying a pair of shoes countersunk in the window-casing, each of said shoes

having an eye at one end and formed with

guides, a pair of disconnected and independ-

ently-operated bites, one for each sash, slid-

ing in said shoes and operated independently

to lock the sashes, a pair of disconnected

and independently-operated rods extending

through the eyes of the respective shoes and

engaging the bites therein, and a spring for

each bite, operating in opposition to the rod

of its bite and arranged between its bite and

a wall of the shoe, substantially as de-

scribed.

5. The combination with a window-casing

having an outer guide-strip, a recessed part- 5
ing-strip and a recessed stop; and the upper
and lower sashes; of a separate shoe for each
window countersunk in the casing; a sepa-
rate block in each shoe, each having a later-
ally-projecting bite, one of which is received
in the recess in the stop and the other in the
recess in the parting-strip; a separate spring
for each block; and a separate push-bar for
each block, operated to force the same in op-
position to the spring thereof; one of said
blocks serving to lock one sash against the
parting-strip and the other block serving to
lock its sash against the outer guide-strip,
and said blocks, shoes, push-bars and springs
being concealed and protected by the part-
ing-strip and stop, substantially as de-
scribed.

6. The combination with the window-cas-
ing, having recessed strips, and the upper

and lower sashes, of shoes countersunk in
said casing and having eyes at their ends,
blocks movable in said shoes and engaged
with the walls of the same, each of said blocks
having a laterally-extending bite projecting 25
into the recess in the contiguous strip from a
place intermediate of its ends and forming a
corner which receives the contiguous corner
of a sash, and each block also having a cut-
away corner, a spring for each block, re- 30
ceived in said cut-away corner, and a longi-
tudinally-movable rod for each block, pro-
jecting through the eye of a shoe and engag-
ing the block therein, substantially as de-
scribed.
